UNITED STATES PATENT OFFICE.

EDWARD JAMES DOVE, OF LONDON, ENGLAND.

MEANS FOR EFFECTING TEMPORARY REPAIRS TO BROKEN AXLES OF MOTOR-CARS.

1,358,532.

Specification of Letters Patent.

Patented Nov. 9, 1920.

Application filed January 2, 1920. Serial No. 349,073.

To all whom it may concern:

Be it known that I, EDWARD JAMES DOVE, of 190 St. John's street, Clerkenwell, London, E. C. 1, England, yeast merchant, a 5 subject of the King of Great Britain, have invented certain new and useful Means for Effecting Temporary Repairs to Broken Axles of Motor-Cars, of which the following is a specification.

10 This invention relates to motor cars of the Ford type, in which the axle casing carries the load, and has for its object to provide improved means whereby the driving axle of such a car, when broken at a point 15 on either side of the differential gear, may be easily and quickly repaired either so far as is necessary in order to permit of the car being safely towed on its own wheels, or so far as is necessary to enable the car to be 20 driven away by its own power.

For the purpose of enabling a car to be towed when either section (right or left hand) of the driving axle of the car is broken, the corresponding wheel is removed, 25 the severed portion of the axle with the attached part of the brake gear is withdrawn, and the roller-bearings are detached from the axle-casing. In place of the severed portion of the axle, there is inserted a 30 spindle adapted externally to fit within the axle-casing and internally to fit over the outer end of that portion of the broken axle which remains connected with the differential gear; this spindle, which passes out 35 through the usual brake-drum, having its outer end portion adapted to receive and hold the previously removed wheel in its usual position; while the spindle is provided with an annular retaining collar for 40 holding it in proper position relatively to the remaining broken portion of the axle.

According to this invention the spindle which is fitted within the axle-casing and which is adapted to fit over the outer end of 45 that portion of the broken axle which remains, is provided with a ring adapted to fit closely within the axle casing and mounted on a ball bearing on the spindle.

The invention is illustrated in the accompanying drawings wherein similar references indicate like parts and wherein Figure 1 is a side elevation of one form of spindle, Fig. 2 is a face view and Fig. 3 is a cross section on the line 3-3 Fig. 2 of a detail, 50 Fig. 4 is a sectional elevation on a smaller scale showing the spindle in position for

use, Figs. 5 and 6 are respectively a plan and a side elevation of a modified form of spindle, Fig. 7 is a sectional elevation on a smaller scale showing the modified form of 60 spindle in position for use and Figs. 8 and 9 are sectional elevations of details.

As shown in Figs. 1 and 4 the spindle *a* has the middle portion *b* of its length made of a diameter to fit easily within the outer 65 end portion of the axle-casing *c* while the inner portion *d* of its length is of reduced diameter and hollow as at *e* so as to fit over the outer end of the axle *f* which remains on the car. The outer portion *g* of the length 70 of the spindle *a* is also of reduced diameter, and is tapered to correspond with the tapered portion of the broken-off portion of the axle *f* so as to be adapted to receive the wheel (not shown); this tapered portion *g* 75 of the spindle *a* being provided with a feather *h* whereby to key the wheel to the spindle, and being screw-threaded at its outer extremity as at *j* to receive a nut *k* for retaining the wheel in position. Mounted upon a ball bearing *m* on the middle portion *b* of the spindle is a ring *n* made of a diameter to fit closely within the outer end portion of the axle-casing *c* while a collar *o* placed on the spindle at the junction between the middle and outer portions *b* and *g* of the length of the spindle is also situated within the outer end portion of the axle 80 casing *c* and is furnished with a thrust-ball bearing *q* and against the thrust-ball bearing *q* is fitted an annular retaining collar *r* 85 formed with a ball race *s* and which embraces a circumferential flange *o'* of the collar *o*; the aperture *t* in the retaining collar *r*, which is preferably rabbeted as at *u* so as 90 to fit over both the flange *o'* and the outer end portion of the axle casing *c*, is prevented from revolving relatively to the 95 brake drum *p* by an arm *v* which projects radially from the retaining collar *r* and has a hole *w* near its extremity whereby the arm *v* may be secured within the brake-drum *p* by means of a bolt *x* passed through said hole *w* and a corresponding hole presented in the drum *p* in consequence of the removal 100 of the brake.

The spindle *a* may be tubular throughout its entire length or throughout the inner and middle portions of its length, as shown, and in order to facilitate lubrication, the enlarged middle portion *b* of the spindle may 110 be formed with grooves running directly as

at y or helically as at z around its periphery, and one of the grooves y may be engaged by the point of a set-pin 10 screwed through the hole presented in the wall of the axle-casing 5 c on the detachment of the usual grease cup.

In the modified form of the invention shown in Figs. 5 to 9 the inner portion d of the spindle is prolonged and is formed with four rows of threaded apertures 11, and 12, 10 lying in axial planes intersecting approximately at right angles, the apertures 11 lying in the one axial plane and the apertures 12 in the other. The apertures 11 in each row are spaced apart a distance equal 15 to twice that intervening between adjacent apertures 12 and while the apertures 11 in both rows are arranged at the points of intersection of two helices, the one right handed and the other left handed the apertures 12, are arranged so that adjacent apertures lie the one in the right handed helix and the other in the left handed helix and in order that the respective helix to which the apertures 12 appertain may be readily 20 recognized the inner portion d of the spindle is engraved or otherwise marked with right and left handed helices 15 and 16 respectively. The threaded apertures 11 and 12 are adapted to receive, on the one hand, 25 grub screws 17 formed with hardened points adapted to project through to the interior of the portion d and to cut into the outer end of the axle f which remains on the car, and on the other hand, a grub screw 18 30 adapted to project through to the interior of the portion d and constitute a stop.

When an axle is broken the wheel is removed and the outer portion of the broken axle is removed. The grub screw 18 is engaged with a threaded aperture 11 or 12, as the case may be, at a distance from the outer end of the spindle approximately equal to the length of said outer portion of the broken shaft, and the grub screws 17 are engaged with threaded apertures 11 at a greater distance from the outer end of the spindle and with threaded apertures 12 which lie in the right handed or left handed helix according as the broken axle is on the 45 left or right hand side of the car respectively. Preferably the grub screws 17 are engaged with the apertures 11 and 12 so as to project successively greater distances into the inner portion d from the inner part 50 of the latter toward the outer part thereof. The spindle is then slidden into position so that the portion d receives into it the outer end of the broken axle f and the spindle is rotated to the right or left as the case may 55 be so as to cause the hardened points of the grub screws 17 to bite into said axle. This rotation of the spindle causes a screw thread to be cut in the axle as shown in Figs. 8 and 9, the thread being started at separate points 60 and ultimately joining up to constitute a

single thread. The length of the screw thread so formed is determined by the grub screw 18 which not only prevents further rotation of the spindle when the desired length of thread has been cut but prevents 70 relative endwise movement of the spindle and the axle f when power is applied through said axle, the direction of the thread tending to draw the spindle farther on to the axle, so that after the wheel has been placed 75 and secured in position on the spindle the car can be driven away under its own power.

I claim:

1. Means for effecting temporary repairs to the broken axle of a motor car having an axle casing and a brake-drum thereon, said means comprising a spindle having one end hollow and adapted externally to fit within the axle casing and internally to fit over that portion of the broken axle which remains, the outer end of said spindle being adapted 80 to receive and hold in position a wheel, and said spindle being provided with means adapted to hold said spindle in proper position relatively to the remaining broken portion of the axle, a ring adapted to fit closely in said axle casing, and a ball-bearing in said ring, said spindle being adapted to revolve in said ball-bearing.

2. Means for effecting temporary repairs 95 to the broken axle of a motor car having an axle casing and a brake-drum thereon, said means comprising a spindle having one end hollow and adapted externally to fit within the axle casing and internally to fit over that portion of the broken axle which remains, the outer end of said spindle being adapted 100 to receive and hold in position a wheel, and said spindle being provided within the brake-drum with means adapted to hold said 105 spindle in proper position relatively to the remaining broken portion of the axle and permit said spindle to rotate independently of said portion, said means comprising an annular retaining collar adapted to embrace 110 said spindle and constitute a bearing therefor, a radially projecting arm on said retaining collar adapted to be secured within the brake drum, a collar on the spindle and a thrust ball bearing adjacent said collar 115 adapted to coat with said retaining collar and prevent endwise movement of said spindle.

3. Means for effecting temporary repairs 120 to the broken axle of a motor car having an axle casing and a brake-drum thereon, said means comprising a spindle having one end hollow and adapted externally to fit within the axle casing and internally to fit over that portion of the broken axle which remains, the outer end of said spindle being adapted 125 to receive and hold in position a wheel, while the inner end of said spindle is provided with adjustable inwardly projecting thread-cutting means adapted to cut 130

a screw thread on said portion of the broken axle.

4. Means for effecting temporary repairs to the broken axle of a motor car having an axle casing and a brake-drum thereon, said means comprising a spindle having one end hollow and adapted externally to fit within the axle casing and internally to fit over that portion of the broken axle which remains, 5 the outer end of said spindle being adapted to receive and hold in position a wheel, while the inner end of said spindle is provided with adjustable inwardly projecting thread-cutting means adapted to cut a screw thread 10 on said portion of the broken axle, and means for limiting the length of thread cut while said spindle is being fitted and when the car is being subsequently driven.
5. Means for effecting temporary repairs 15 to the broken axle of a motor car having an axle casing and a brake-drum thereon, said means comprising a spindle having one end hollow and adapted externally to fit within the axle casing and internally to fit over 20 that portion of the broken axle which remains, the outer end of said spindle being adapted to receive and hold in position a wheel, while the inner end of said spindle is provided with adjustable inwardly 25 projecting thread-cutting means adapted to cut a screw thread on said portion of the broken axle, said thread-cutting means being adapted to be readily adjusted so as to cut right and left handed threads, alternatively 30 at will.

6. Means for effecting temporary repairs to the broken axle of motor car having

an axle casing and a brake-drum thereon, said means comprising a spindle having one end hollow and adapted externally to fit 40 within the axle casing and internally to fit over that portion of the broken axle which remains, the outer end of said spindle being adapted to receive and hold in position a wheel, while the inner end of said spindle 45 is formed with a series of apertures some of which are disposed on a right handed helix, some of which are disposed on a left handed helix and some of which are disposed at the points of intersection of said right and left 50 handed helices.

7. Means for effecting temporary repairs to the broken axle of a motor car having an axle casing and a brake-drum thereon, said means comprising a spindle having one end hollow and adapted externally to fit within the axle casing and internally to fit over that portion of the broken axle which remains, the outer end of said spindle being adapted to receive and hold in position a wheel, 55 while the inner end of said spindle is formed with series of threaded apertures some of which are disposed on a right handed helix, some of which are disposed on a left handed helix and some of which are disposed at the 60 points of intersection of said right and left handed helices, and grub screws adjustable in some of said threaded apertures, one of said grub screws being adapted to constitute a stop while the others of said grub screws 65 are formed with hardened points adapted to cut a screw thread in said broken axle.

EDWARD JAMES DOVE.
